UNITED STATES PATENT OFFICE.

LOUIE T. LEWIS, OF FLETCHER, OKLAHOMA.

REINFORCED-CONCRETE RAILWAY-TIE.

1,027,263.

Specification of Letters Patent. Patented May 21, 1912.

Application filed October 6, 1911. Serial No. 653,159.

To all whom it may concern:

Be it known that I, LOUIE T. LEWIS, a citizen of the United States, and a resident of Fletcher, in the county of Comanche and 5 State of Oklahoma, have invented an Improved Reinforced-Concrete Railway-Tie, of which the following is a specification.

My invention is a composite railway tie formed of cement or concrete and a reinforce 10 consisting of a skeleton metal frame. The latter is of peculiar construction, it being formed of three principal parts which are so constructed and connected that the frame combines maximum strength, rigidity, and lightness.

In the accompanying drawing, Figure 1 is a longitudinal section of the complete tie. Fig. 2 is a plan view of the top plate forming 20 part of the reinforcing frame. Fig. 3 is a perspective view of the reinforcing frame.

The steel, skeleton, reinforcing frame is formed of three oblong rectangular plates, to wit, top and bottom plates 1 and 2, which are spaced apart vertically, and an interposed brace or truss 3, all of which are provided with longitudinal central slots 4 and other shorter slots 5 located near the ends.

The top plate 1 is flat and the bottom plate 2 is also flat save its end portions, which are bent twice at a right angle, thus forming terminal flanges 6 that serve as shoulders supporting the top plate 1. The brace 3 is arched at the middle, or formed 35 with an obtuse angle, whose central portion is riveted at 7 to the top plate 1, while its flat depressed or bottom portions 8 are riveted to the bottom plate 2, and its end portions, which project upward at an angle 40 of about 45°, are riveted at 10 to and between the ends of the top and bottom plates 1 and 2. Thus the brace 3 is rigidly connected with and ties together the top and bottom plates and forms part of a rigid 45 structure having maximum strength, rigidity, lightness, and durability.

To form the complete tie, the described skeleton frame is embedded in, or completely

covered by, cement or concrete, as shown in Fig. 1. In applying the concrete, it enters 5 and lies in the several slots 4 and 5 of the frame parts 1, 2, and 3, and thus takes a firm hold on the frame. The slots further serve to reduce the weight of the frame as well as its cost of manufacture. The rails α are secured on the concrete body of the tie by means of bolts 11 which are mainly embedded in the concrete and passed through the plates 1, 2 and 3 at the points 12 where suitable holes are provided, the upper ends 60 of the bolts projecting above the body of the tie and the nuts applied thereto impinging on the rail base. The rails may be thus easily and quickly secured on the tie or released therefrom as conditions require. 65

What I claim is:

1. The improved railway tie, comprising a cement body and a reinforcing metal frame which is embedded in the cement, the same being formed of slotted rectangular 70 top and bottom plates, the latter having ends bent upward at a right angle, and an interposed brace consisting of a plate having a raised obtuse-angled central portion, and angular depressions near the ends which are 75 secured between the top and bottom plates, all the plates being riveted together at their several points of contact and the top and bottom plates being provided with coincident holes for reception of rail bolts, substantially as described.

2. The improved reinforce for cement ties, consisting of a skeleton frame formed of top and bottom plates and an interposed plate serving as a truss and brace, the central portion of the latter being arched and riveted to the top plate and its end portions depressed and riveted to the bottom plate, its terminals being secured between the ends of the top plate and the bottom plate, as 90 shown and described.

LOUIE T. LEWIS.
